US0D1022657S

(12) **United States Design Patent** (10) **Patent No.:** **US D1,022,657 S**
Minale (45) **Date of Patent:** **** Apr. 16, 2024**

(54) **DOOR HANDLE**(71) Applicant: **Buster and Punch Limited**, Stamford (GB)(72) Inventor: **Massimo Minale**, London (GB)(73) Assignee: **Buster and Punch Limited**, Stamford (GB)(***) Term: **15 Years**(21) Appl. No.: **29/842,006**(22) Filed: **Jun. 9, 2022****Related U.S. Application Data**

(62) Division of application No. 29/744,701, filed on Jul. 30, 2020, now Pat. No. Des. 958,633.

(30) **Foreign Application Priority Data**

Feb. 6, 2020 (EM) 007667357-0001
 Feb. 6, 2020 (EM) 007667357-0002
 Feb. 6, 2020 (EM) 007667357-0003

(51) **LOC (14) Cl.** ..... **08-06**(52) **U.S. Cl.**USPC ..... **D8/308**(58) **Field of Classification Search**

CLAIM

The ornamental design for a door handle, as shown and described.

DESCRIPTION

FIG. 1 is an isometric view of a door handle showing a first embodiment of the design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is an isometric view of a door handle showing a second embodiment of the design.

FIG. 9 is a front elevation view thereof.

FIG. 10 is a rear elevation view thereof.

FIG. 11 is a right side elevation view thereof.

FIG. 12 is a left side elevation view thereof.

FIG. 13 is a top plan view thereof; and,

FIG. 14 is a bottom plan view thereof.

The broken lines shown in the drawings illustrate portions of the door handle that form no part of the claimed design.
